MECHANISM FOR CUTTING SHEET MATERIAL

Application filed October 8, 1928. Serial No. 311,017.

This invention relates to a mechanism for cutting sheet material, and finds one particular adaptation in the asphalt shingle industry wherein shingles or shingle strips, are cut from a sheet of prepared roofing material. More specifically, my invention has reference to the production of shingles or shingle strips made from a base of felted or similar fibrous material, saturated with a waterproofing substance, and coated on one or both of its surfaces with waterproofing material, which latter may have partially embedded therein a layer of crushed mineral, such as slate or the like, which is intended to mask the waterproofing layer from the deteriorating action of the sun, and to also provide a decorative finish for the product. Prepared roofing as thus briefly described, is being manufactured at the present time in enormous quantities, a large part of the output consisting of shingles, or so-called strip shingles, comprising a slab section of predetermined length formed with shingle simulating tabs of any desired configuration. One objection to this type of roofing strip is its flat appearance and the monotonous regularity of the lines that are visible to the eye of the observer. In order to relieve the monotony of the straight and even-line appearance of this type of roof, it has been proposed to produce shingles the exposed edges of which are formed on irregular lines so that the completed roof would present an appearance of irregularity at the exposed areas, resembling somewhat the appearance of a thatched roof, or a roof of broken slate.

My invention is particularly concerned with the provision of simple means for continuously producing shingles or strips having irregular butt edges, the irregularity in the configuration of the tab edges of successive shingles as they are produced, varying continuously through a period or cycle sufficiently large to enable the shingles to be packaged substantially in the order in which they are severed from the sheet so that when laid up on the roof, the regular straight line appearance now common to the ordinary square butt shingles will be avoided to the end that the roof may take on the more desirable ap-

pearance of irregularity or unevenness, and thereby also accentuate the thickness of the exposed butt edges of the shingles.

In carrying out my invention, I provide means for slitting the sheet longitudinally along a sinuous, broken or other irregular line, to form separate strips or sections having complimentary edges along the line of severance. The means for producing this irregular line of cut may be designed to repeat, at stated intervals, the configuration of the longitudinal slit. I provide also means for then severing from the separate sections the shingles or strip shingles of desired length, and in accordance with one of the novel features of my invention, I co-ordinate the last named means with the longitudinal slitting device in such a way that repetition in the identity of configuration of the exposed edges of the elements produced, occurs only at relatively long intervals, during which period a sufficiently large number of shingles of varying butt or tab edge configuration has been produced, to permit the shingles to be packed directly from the machine so that when applied on the roof they will form, in the completed roof, areas that deviate in pleasingly irregular fashion from the straight line effects usual in this type of roofing.

One embodiment of my invention will be hereinafter described more fully and is shown on the accompanying drawings, in which

Figure 1 represents a section through the cutting mechanism,

Figure 2 is a plan through part of the mechanism shown in Figure 1, as viewed along line 2-2 of Figure 1,

Figures 3 and 4 illustrate, graphically, variations that may be achieved in accordance with the principles of my invention,

Figure 5 shows, in perspective, a pair of complimentary shingles having irregular butt edges as produced by my invention, and

Figure 6 illustrates other forms of shingles that may be severed from the sheet.

Figure 7 represents a plan view of a fragment of a roll with staggered cutting elements.

Referring in detail to the drawings, the

numeral 20 indicates a web of roofing base which may comprise a felted foundation of rag, asbestos, or similar fibers, impregnated with asphalt or similar waterproofing material, coated on one or both of its faces with blown asphalt or the like, and surfaced with crushed slate or other suitable mineral. The sheet is shown as it is being fed to my improved mechanism for cutting therefrom shingles of the character described. As shown, I prefer to perform the cutting operation from the underside of the sheet by means of a circular slitting knife 21 formed on a drum or cylinder 22 and co-operating 15 with a suitable bed roll 23, mounted above the cylinder 22. The sheet may be supported by a frame or table 24, slotted as at 25, to accommodate the confronting faces of the cutting roll and its cooperating bed roll. The 20 cutting roll 22 is fixed to a rotatable shaft 22a and the roll 23 is similarly fixed to a shaft 23a. The knife blade 21 is disposed around the cylinder 22 substantially at the mid-point thereof, and may comprise either one continuous blade having an undulating cutting edge or a series of blades spaced around the periphery in such manner as to produce a slit of broken configuration in the sheet 20 as the latter passes between the cutting roll and its 25 cooperating bed roll 23, to thereby provide separate, but complementary sections 20a, and 20b.

Mounted adjacent the rolls 22 and 23 are a pair of cooperating rolls 26 and 27 which 30 are adapted to sever from the separate sections 20a and 20b, shingle strips of the desired length. Of this pair of rolls, the roll 26 constitutes the cutting roll and the roll 27 the bed roll. The cutting roll may also be 35 equipped with means for cutting slots in the separate sections, so as to provide the finished strips with shingle simulating tabs. In the particular embodiment shown in Figures 1 and 2, the cutting roll 26 is designed to sever 40 from the separate sections, shingles as shown in Figure 5, each having a plurality of tabs 31 and intervening rectangular tab-defining slots 32, the butt edges of the elements being of irregular configuration conforming to the 45 position of the knife 21. It will be understood, of course, that the knife 21 may be arranged for producing longitudinal slits of configurations other than that shown in Figures 2 and 5. Thus, the knife may comprise a 50 series of irregularly staggered smaller knives 70, 71 and 72 as shown in Figure 7 so as to produce an effect like that illustrated in Figure 6, wherein the butt edges 33b of the shingles 30b cut from sheet, are shown as following an irregular broken line. In order to 55 cut the slots 32 in the shingle strips, the roll 26 may be formed on its periphery with a series of rectangular die-pieces 36 spaced and dimensioned in accordance with the desired 60 size of the tabs and tab-defining slots. I

have shown the several die-pieces 36 as being of equal dimensions and equally spaced around the roll so as to form slots identical in size and spaced evenly apart, but it will be understood, of course, that these die-pieces 65 may be of varying dimensions and spaced at varying intervals around the periphery of the roll 26, so as to produce shingle strips having differently dimensioned tabs and tab-defining slots. A pair of knives 37 extend from a point near the middle of the ends of one of the die-pieces 36 to the end of the roll 26, these knives 37 being adapted to sever the successive strips at their ends, from the separate sections 20a and 20b respectively. The 70 length of the strips produced will obviously depend upon the circumferential dimension of the roll 26. In actual practice, for example, this roll may be dimensioned so as to produce strips which are 36 inches in length. 75

In accordance with my invention, the mechanism for severing the successive strips from the separate sections 20a and 20b as produced by the longitudinal slit formed by the knife 21, is related to the means for producing this longitudinal slit in such a way that the two operate more or less out of phase with one another. In order to accomplish this result, I construct the roll carrying the knife 21 of a different diameter than that of the roll carrying the severing knives 37. 80 These two rolls are then arranged to rotate at different axial speeds such that their peripheral speed will be substantially equal so that the web of roofing may be fed continuously therethrough at the desired speed of travel. In Figures 1 and 2 I have shown, for purposes of illustration, the roll 22 as being somewhat greater in diameter than the roll 26. In actual practice, however, where the roll 26 is designed to sever strips 36 inches in length, the maximum benefits of 85 my invention may be attained by constructing the roll 22 of a diameter such that the circumference of the knife 21 will be only 90 slightly greater than the circumference of the roll 26. Advantageously, for example, the circumference of the cutting knife 21 may be 37 inches where the roll 26 is 36 inches in circumference. It will be seen, 95 therefore, that by rotating the rolls 22 and 26 at the same peripheral speed, the severance 100 of the successive strips 30 from the separate sections of the web, by the knives 37 will be 105 out of phase with the sinuous or irregular slit formed by the knife 21. Thus, assuming 110 any point along the slit produced by the knife 21, as a starting point, it will be seen 115 that before the knife 21 makes one complete revolution in its rotation, the knives 37 will 120 have severed from the sheet a strip of a length approximately one inch less than the linear extent of one complete cycle of the longitudinal slit formed in the sheet by the knife 21. 125 As the rolls continue in their rotation,

the strips 30 are successively severed from the sheet in continual out of phase relation with the longitudinal slit, until as will be manifest, a point is soon reached in the rotation of the rolls where the cut produced by the knives 37 coincides substantially with the same relative point along the longitudinal slit corresponding to the starting point above referred to, whereafter the period or cycle 10 will repeat itself. In the specific example mentioned, it will require approximately 37 complete revolutions of the roll 26 before there is a repetition in the cycle and hence, a series of approximately thirty-seven pairs 15 of strips are severed from the sheet, the tab-edge configuration of each one differing more or less from that of its neighbor; moreover the opposed pairs of strips as cut from the separate sections 20a, 20b, being complementary will, when both are placed in the same 20 relative position with respect to their butt edges, present butt edges which are slightly different in configuration. Hence in reality, a series of approximately seventy-four 25 shingles each of different butt edged configuration, will be produced before there is any repetition in the series.

In order to rotate the rolls 22 and 26 at the properly related axial speeds any suitable form of transmission may be employed. I have shown, for example, in Figures 1 and 2, a pulley 40 mounted on a shaft 41 and driven by a belt or chain 42 from any convenient source of power. The shaft 41 may 25 have fixed thereon a gear 43 meshing with a larger gear 44 affixed to the shaft 22a.

The shaft 22a also has affixed thereto a driving gear-wheel or pulley 46, which is connected by a chain or belt 47 to a gear 40 wheel or pulley 48 fixed to the shaft 26a upon which the cutting roll 26 is mounted. The driven pulley 48 should be sufficiently smaller than the driving pulley 46 to enable the roll 26 to rotate at an axial speed sufficiently in 45 excess of the axial speed of the roll 22, to equalize the peripheral speed of the two rolls. This is shown in more or less exaggerated form in Figures 1 and 2 for purposes of clear illustration. In this way the 50 sheet may be continuously and uniformly fed through the cut mechanism and severed, as already described. The severed strips may be delivered to a conveyor 50, one end of which is located adjacent the cutting roll 26, and from the opposite end of which the strips 55 may be stacked as at 51, directly in the order in which they are delivered from the cutting mechanism, to be packaged when a sufficient number have been accumulated.

In Figures 3 and 4 I have shown by graphic illustration, variations that may be produced in carrying out my invention merely by varying the relative size of the cutting rolls 22 and 26. Thus, as shown in 60 Figure 3 the longitudinal curved or irregu-

lar slit is indicated at X, the letters A indicate the period within which the cutting knife 21 will make a complete revolution and the transverse lines 60 indicate the lines of severance produced by the cutting knives 37 to form the shingle strips 30a, having the irregularly shaped butt edges. In this figure (as well as in Figure 4) the tab-defining slots in the strips are omitted for purposes of clearness. As will be evident from this figure the roll 22 would need to be much greater in diameter than the roll 37, since as here illustrated, the distance between a pair of adjoining points A, representing one complete revolution of the roll 22, is slightly less than three times as great as the distance between a pair of transverse slits 60, representing the end edges of the severed strips. The frequency with which identically configured strips will be produced, would depend again upon the mathematical relationship between the length of the strips produced, and the linear distance between successive points representing one complete revolution of the central slitting knife. 90

Similarly, in Figure 4, I have shown graphically an effect that might be produced by the use of a cutting knife 22 smaller in diameter than the cutting knife 26. In this figure, the distance between the points B indicate the interval within which the circular knife makes one complete revolution while the transverse lines 60b indicate again the end edges of the strips as produced by the cutting knives 37. In this figure, again, by 95 selecting a roll 22 of a diameter less than the distance between the lines 60b and which is not evenly divisible into this distance, a great variety of strips may be successively cut from the sheet before there is any recurrence of strips of identical butt edge configuration. 100

It will be understood that while I have described my invention in connection with the manufacture of the so-called strip shingles, the novel features herein disclosed may also be employed with advantage in the production of individual shingles having irregular butt edges, the irregularity being more or less different in a considerable number of successive shingles cut from the sheet. 110

By the term "sinuous" as employed in the claims, I mean any more or less irregular effect, whether along a curve, a broken line, a combination of these two, or otherwise. 120

I claim as my invention:

1. Mechanism for cutting sheet roofing material to produce shingle elements of varying butt-edge configuration, comprising means for slitting the sheet longitudinally along a 125 sinuous line the pattern of which is repeated at regular intervals by the continued operation of said means, and means for severing the sheet transversely thereof at predetermined intervals, said last named means op- 130

- erating out of phase with the first named means.
2. Mechanism for cutting sheet material, comprising a rotatable knife for slitting the sheet longitudinally along a sinuous line, said knife being of a predetermined circumferential dimension, whereby to form the sheet into separate sections each having a sinuous edge the pattern of which is repeated at intervals corresponding to the circumferential dimension of said knife, and means for severing said sections transversely thereof at intervals differing in linear extent from the first named intervals.
3. Mechanism for cutting sheet material, comprising a rotatable knife for slitting the sheet longitudinally along a sinuous line, said knife being of a predetermined circumferential dimension, and a rotatable cutting roll for severing the sheet transversely thereof, said cutting roll being of a circumferential size different from that of the said rotatable slitting knife.
4. Mechanism for cutting sheet material, comprising a rotatable knife for slitting the sheet longitudinally along a sinuous line, said knife being of a predetermined circumferential dimension, and a rotatable cutting roll for severing the sheet transversely thereof at predetermined regular intervals differing in linear dimension from that corresponding to the circumferential dimension of said knife.
5. Mechanism for cutting sheet material, comprising a rotatable knife for slitting the sheet longitudinally along a sinuous line, said knife being of a predetermined circumferential dimension, and a rotatable cutting roll for severing the sheet transversely thereof, said cutting roll being of a circumferential size different from that of the said rotatable slitting knife and operating at the same peripheral speed as said knife.
6. Mechanism for cutting sheet material, comprising in combination, a rotatable knife for slitting the sheet longitudinally along a sinuous line, and a rotatable cutting roll for severing the sheet transversely thereof, said roll being smaller in circumference than said knife but operating at equal peripheral speed therewith.
7. Mechanism for cutting sheet material, comprising in combination, a rotatable knife for slitting the sheet longitudinally along a sinuous line, and a rotatable cutting roll for severing the sheet transversely thereof, said knife and roll being of different circumferential dimensions and operating at different axial speeds such as to equalize the peripheral speed of the knife and roll, said roll being provided with means for forming spaced transverse slots in the sheet.
8. Mechanism for cutting sheet material, comprising in combination, a rotatable knife for slitting the sheet longitudinally along a sinuous line, and a rotatable cutting roll for severing the sheet transversely thereof, said knife and roll being of different circumferential dimensions neither of which is an even multiple of the other, and operating at different axial speeds such as to equalize their peripheral speeds.
